UNITED STATES PATENT OFFICE.

KARL BAUMANN, OF URMSTON, AND ARTHUR EDWIN LEIGH SCANES, OF ASHTON-ON-MERSEY, ENGLAND, ASSIGNEES TO THE BRITISH WESTINGHOUSE ELECTRIC AND MANUFACTURING COMPANY, LIMITED, A COMPANY OF GREAT BRITAIN.

CONDENSING-STEAM-TURBINE INSTALLATION.

1,372,929.

Specification of Letters Patent. Patented Mar. 29, 1921.

Application filed January 31, 1917. Serial No. 145,709.

To all whom it may concern:

Be it known that we, KARL BAUMANN, a citizen of the Confederation of Switzerland, and a resident of Urmston, in the county of 5 Lancaster, England, and ARTHUR EDWIN LEIGH SCANES, a subject of the King of Great Britain, and a resident of Ashton-on-Mersey, in the county of Chester, England, have invented a new and useful Improvement 10 in or Relating to Condensing-Steam-Turbine Installations, of which the following is a specification.

In condensing steam turbine installations it has already been proposed to divide up 15 the steam flowing from the last row or rows of blades of the turbine to the condenser by means of guide walls, diaphragms or the like located in the exhaust casing of the turbine, and the present invention relates to 20 condensing steam turbine installations in which the exhaust casing of the turbine is provided with such guide walls, diaphragms or the like, and has for its object to provide an improved construction and arrangement 25 of condenser for use with a turbine of the above kind.

In a surface condenser the temperature of the water flowing through the condenser tubes varies, and as the rate of condensation 30 depends upon the temperature difference between the steam and temperature of the water, the cooler portions of the condenser will condense more steam than the hotter portions, with the result that in an installation comprising a turbine and a surface condenser there is a tendency for steam to be drawn by the cooler condensing surface from portions of the exhaust outlet of the turbine other than those portions located 35 immediately above the cooler condensing surface. This tends to increase the length of the path of the steam flowing to the condenser and to increase the pressure drop accordingly. A similar effect is also observable 40 in condensers of the jet or direct contact type.

In order to obviate this difficulty, according to the present invention some or all of the aforesaid guide walls, diaphragms or 45 the like, in the exhaust casing of the turbine are continued beyond the exhaust outlet of the turbine through into the condenser itself in such a manner that the condenser is divided up into a number of compartments

each of which will act as a separate condenser. 55

Stated in another way, the condenser is provided with partitions or the like adapted to form continuations of some or all of the guide walls, diaphragms or the like in the 60 exhaust casing of the turbine, which partitions divide up the condenser into a plurality of compartments in such a manner that each of said compartments will act as a 65 separate condenser.

In order to obtain approximately equal condensation in each compartment of the condenser thus formed the flow of cooling water is preferably so arranged that in the case of a surface condenser the temperature 70 of the water in the tubes in each of the compartments is as uniform as possible. This may be accomplished by arranging that the water will flow once only through each compartment. Each compartment will in this 75 way constitute in effect a single flow condenser, but although in this way the temperature of the water in each compartment of the condenser is rendered as uniform as 80 possible, the temperature of the water in the several compartments of the condenser will differ.

The invention may be carried into effect in a variety of ways, some of which will now be described with reference to the accompanying drawings, in which Figure 1 is an elevation, partly in section, of a turbine having its exhaust casing constructed and arranged as shown in the specification of the British Patent No. 1713 of 1916, and a central cross-sectional view of a condenser constructed in accordance with this invention and adapted to be used with a turbine having an exhaust casing of the kind indicated. 85

Fig. 2 is a sectional view on line II—II 95 of Fig. 1.

Fig. 23 is a sectional view on line III—III of Fig. 1.

Fig. 4 is a view taken on the line IV—IV 100 of Fig. 1.

Fig. 5 is a developed view of the extraction chamber of the condenser shown in Figs. 1, 2, and 3.

Fig. 6 is a plan view of another form of condenser constructed in accordance with 105 this invention and adapted to be used with a turbine having an exhaust casing of the kind shown for example in Figs. 1 and 2,

Fig. 7 is a longitudinal sectional view of the condenser shown in Fig. 6 and Fig. 8 a cross section on the line VIII—VIII of Fig. 6.

5 Fig. 9 is a sectional view taken on the line IX—IX of Fig. 8.

In the installation shown in Figs. 1 to 5 the turbine is of the kind described in the specification of Patent No. 105,933 of 1916, 10 the steam being exhausted from a plurality of rows of moving blades, as here shown from four rows of moving blades, and the exhaust casing for the turbine is of the kind having segregating partitions or diaphragms. The 15 guide 22 for directing the steam flowing from the antepenultimate row of moving blades is extended until it reaches the side wall 23 of the exhaust casing 1 of the turbine, the longitudinal partition wall 7 of 20 the condenser 2 making joint with the extended guide 22 at the exhaust outlet of the turbine. In addition the exhaust casing of the turbine is provided with a central vertical web 24 which extends from a point 25 closely adjacent to that portion of each of the rows of moving blades from which the steam is exhausted to the inclosing casing of the turbine exhaust. At the exhaust outlet the vertical web 24 makes joint with the 30 transverse partition wall 3 of the condenser. The condenser is thus divided into four separate compartments A, B, C, D, of which compartments A and B receive and condense the steam flowing from the last and 35 penultimate rows of moving blades of the turbine while compartments C and D receive and condense the steam flowing from the two preceding rows of moving blades. Further, by reason of the vertical web 24 40 compartments A and B and compartments C and D each respectively receive and condense the steam flowing from one half only of said rows of moving blades. Each of the compartments A, B, C, D, is provided with 45 an atmospheric relief valve so that the plant may be run non-condensing if desired, the relief valves for compartments A, B and C being indicated respectively at 29, 29^a and 29^b, it being understood that a similar valve 50 (not shown) is provided for compartment D.

A developed view of the condensate extraction chamber 9 is shown in Fig. 5, from which it will be seen that the level of the water in the various compartments of the 55 condensate extraction chamber 9 varies in accordance with the vacuum obtaining in each of said compartments. The water in said chamber however forms a seal so that a single extraction pump may be connected 60 to the outlet 10.

In those cases in which condensers constructed in accordance with this invention are used in conjunction with turbines, the steam from which is exhausted from a plurality of rows of moving blades, such as is 65

the case in the construction hereinabove described with reference to Figs. 1 to 5, it is preferred to arrange that the steam leaving the row or rows of blades nearest the high pressure end of the turbine passes into the 70 compartments or compartments of the condenser in which the lower vacua exists. This is carried out in the construction described with reference to Figs. 1 to 5, as it will be seen that the steam leaving the two 75 rows of moving blades nearest the high pressure end of the turbine enters the compartments C and D of the condenser in which a lower vacuum (higher absolute pressure) exists than in the compartments 80 A and B as the water passing through the compartments C and D is on the second flow and is therefore at a higher temperature than when it passed through the compartments A and B.

85 A further improvement consists in heating the condensate in the steam space of that compartment of the condenser operating at the highest temperature to a temperature approximately equal to the temperature of the steam entering that compartment. This can be accomplished either by placing a surface heater in the steam space of the compartment operating at the highest temperature through which heater the condensate is passed, or by injecting the condensate into the steam space of said compartment, in which case the condensate will be heated up by direct contact with the steam therein.

90 The invention may also be carried out in such a way that the vacuum in each compartment of the condenser is maintained approximately the same. This is accomplished by so constructing the condenser that the 95 area of the condensing surface in each compartment is varied in accordance with the temperature of the cooling water passing therethrough, the compartment supplied with the coldest water having the smallest 100 condensing surface, while the compartment adjacent to the water outlet will have the largest condensing surface. In other words, the condensing surface in each compartment is so proportioned that the weight of steam 105 condensed per unit area of surface is approximately inversely proportional to the difference in temperature of the steam and the temperature of the water.

110 With the construction above described and 115 illustrated it will be readily understood that the steam flowing from the last rows of moving blades is divided by the walls 24 and the diaphragm 22 in the exhaust casing of the turbine into four separate volumes each 120 of which volumes passes into a separate compartment of the condenser. The vacuum obtaining in the four compartments of the condenser will vary, being highest in that compartment through which the condensing 125

water first flows and lowest in that compartment through which the condensing water last flows before passing away through the water outlet 14. The partition walls 3 and 5 7 extending downward into the extraction chamber 9 enable a water seal to be formed by the condensate in this chamber to compensate for the varying vacua obtaining so that a single extraction pump only may 10 be used. The air and non-condensable gases may be extracted from the several compartments of the condenser by providing an air pump for each compartment or by means of a multiple stage air pump, or 15 in any other way found suitable. Preferably, however, the condenser is so constructed that the vapors and non-condensable gases are discharged from that compartment of the condenser operating at the highest 20 temperature into the compartment having the next lower temperature and thence through the remaining compartments of successively decreasing temperatures until the compartment having the lowest temperature 25 is reached from which the vapors and non-condensable gases are extracted by a single pump or other air extracting device.

One such construction in which this arrangement is carried into effect is illustrated 30 in Figs. 6 to 9 of the drawings. The condenser is here, as in the construction shown in Figs. 1 to 5, provided with partition walls 3 and 7 dividing the condenser into four separate compartments which, for convenience, will 35 be referred to in the description of these figures by the letters A, B, C, D. Portions of each of the compartments are divided off by plates to form air cooling spaces and also a communication channel between adjoining 40 compartments through which the vapors and non-condensable gases may pass from one compartment to the next in the manner described above. The plate in compartment D is shown at 15, in compartment C at 16, in 45 compartment B at 17 and in compartment A at 18. None of the plates 15 to 18 extend the full length of the compartment so that vapors and non-condensable gases may pass from each of the compartments proper into 50 the passages formed between said plates and the shell of the condenser or the partition wall 7, as the case may be. As will be seen, from Figs. 9 and 7 apertures are also provided in the partition wall 3 and in the left-hand end of the partition wall 7 through which the vapors and gases flowing from one compartment to the next may pass. The circulating water last flows through compartment D, which compartment therefore 55 operates at the highest temperature and the flow of the vapor and gases from this compartment through compartments C, B and A in succession, in conjunction with the vapor and gases from other compartments, is 60 indicated by the arrows in Figs. 6 and 9.

Additional plates 19 and 20 in compartment A form a pocket which leads to the air outlet 21 to which the air pump or other air extracting device is connected in the usual way. The passages above referred to, 70 through which the air and vapors are discharged from one compartment into the next succeeding compartment, should, as shown, be relatively small so that a minimum amount of steam will be passed from 75 one compartment to another through such passages.

For the sake of clearness no discharge outlet for the condensate from the several compartments of the condenser shown in Figs. 80 6 to 9 has been indicated. Each of such compartments may have a separate discharge outlet which may conveniently be connected together by siphon legs to compensate for the different vacua obtaining in said compartments and allow of a single condenser extraction pump being used, or said condensate discharge outlets may be of the form shown in Figs. 1 and 2. If it is desired to adapt the plant so that it may be run non-condensing if necessary, an atmospheric relief valve should be provided for each compartment into which the condenser is divided, as shown in Figs. 1 and 3.

While we have illustrated our invention as 95 embodied in a turbine utilizing a plurality of secondary sections in which the motive fluid is fractionally expanded throughout a number of concentrically arranged annular rows of moving blades and stationary vanes, 100 we wish it to be specifically understood that we do not limit our invention to the arrangement shown and described, and that any type of turbine may be utilized without departing from the spirit and scope of the invention as set forth by the appended claims. 105

What we claim as our invention is:

1. In combination with an axial flow steam turbine having a stage or section provided with means for dividing the steam flowing 110 therethrough into annular portions, a condenser having a plurality of separate condensing compartments each arranged to receive the steam of one or more of said annular portions. 115

2. The combination with an axial flow steam turbine having a stage or section provided with blading structures so arranged as to segregate the steam into separate concentric annular portions, a condenser having 120 a plurality of separate condensing compartments each receiving the steam of one or more of said portions.

3. In combination with an axial flow steam turbine having a stage or section provided 125 with blades constructed in multiple tiers, a condenser provided with a plurality of separate condensing compartments each of which is arranged to receive the steam from one or more of said tiers.

4. In combination with a steam turbine having a stage or section provided with means for segregating the steam flowing therethrough into separate portions, a condenser provided with separate condensing compartments each arranged to receive one or more of said separate portions, said condenser being so constructed that the condensing water flows once only through each of said compartments.

5. In combination with a steam turbine having a stage or section provided with means for segregating the steam flowing therethrough into separate portions, a condenser provided with separate condensing compartments of different area each arranged to receive one or more of said separate portions.

6. In combination with an axial flow steam

turbine having a stage or section provided with means for segregating steam flowing therethrough into separate portions and an exhaust casing divided into separate compartments through which one or more of such separate portions flow, a condenser having separate condensing compartments each communicating with one of the compartments of said exhaust casing; said condensing compartments being arranged to act as separate condensers.

In testimony whereof we have hereunto subscribed our names this second day of January 1917.

KARL BAUMANN.

ARTHUR EDWIN LEIGH SCANES.
